FRACTIONATION AND DISTILLATION TRAY
STRUCTUREJames M. Ballenger, Millington, N. J., assignor to
Standard Oil Development Company, a corpo-
ration of Delaware

Application March 29, 1952, Serial No. 279,300

7 Claims. (Cl. 261—114)

1

The present invention relates to an improved fractionation and distillation means. The invention is particularly concerned with the construction of the individual trays such as are employed in fractionation and distillation towers or the like. More particularly, the invention is concerned with such a tray structure having high rigidity and strength, although employing component parts of relatively light weight materials. The invention is also concerned with the provision of a fractionation or distillation tray structure substantially providing the operating benefits of a conventional bubble cap tray while affording substantially the economy of a simple perforated tray.

It is an object of the invention to provide a fractionation tray of relatively light weight and simplified design which may be easily and cheaply manufactured and assembled for use. It is contemplated that assembly and installation of the tray structure may be accomplished with a minimum number of individual parts and to accomplish a maximum strength in the assembled structure while using relatively light materials.

The invention and its objects may be more fully understood from the following description when read in conjunction with the accompanying drawing, in which:

Fig. 1 is a horizontal section through a fractionation tower or other vessel of the character contemplated with certain elements of the complete tray broken away in order to show a typical supporting structure for the tray.

Fig. 2 is a partial, enlarged vertical section through a portion of a vessel such as contemplated by Fig. 1, the section being taken substantially along the line II—II of Fig. 1, and

Fig. 3 is a vertical section through a portion of a tray structure as shown in Figs. 1 and 2 illustrating an alternate means for mounting adjoining tray sections with reference to the supporting structure therefor and also with reference to special distributing baffle means in conjunction therewith.

Referring to the drawings in greater detail in Figs. 1 and 2, the numeral 1 designates the shell of the fractionating tower which is provided with a vertically spaced series of transverse trays substantially as shown. In a cylindrical tower, as shown, each tray has a generally circular shape conforming to the interior dimensions of the tower and supported therein as by means of a truss member 2 and associated purlins 3 and by means of an annular ring member 4. The truss and purlin structure are supported in the tower

2

in any conventional fashion such as by means of angular supports 5, which may be welded to the inner wall surface of the shell 1. Each of the tray members is constructed so as to provide an open segment adjacent the tower wall which permits liquid flow downward from tray to tray in the tower. In locating the trays in the tower, the segmental openings in the several trays are positioned so as to be diametrically opposite from tray to tray and provide for cross flow of a liquid over the trays in succession. Each tray is also provided with a downcomer member including a weir portion 6 extending upwardly to a level above the tray and a baffle portion 7 extending downwardly below the tray into vertically spaced relation to the tray next below. Conventionally, the lower end of baffle portion 7 is disposed at a level lower than that of the upper end of an opposite weir portion 6. In a cylindrical tower the weir and baffle portions forming the downcomer, extend across the tower as a chord and into contact at opposite ends with the inner wall surface.

The present invention relates particularly to the construction of the tray members employed, and to the arrangement and relationships of their structural parts, as well as to the manner in which they are formed and assembled or mounted in a tower of the character described. These features of the invention are more specifically illustrated in Figs. 2 and 3.

Two typical forms of the tray construction contemplated are illustrated in Fig. 2. In the drawing, the upper one of the two trays shown is designed to be assembled in situ and the tray member is composed of a plurality of sectional plate elements. The lower plate elements 8 are of a uniform design provided with substantially flat peripheral edge portions 8a. Adjoining plate edge portions are straight and adapted for disposition in spaced, substantially parallel relation, coextensively with tray support members 2 and 3, while those edge portions adjoining a wall of the vessel are shaped to conform with the vessel wall. The several lower plate sections 8 are assembled and secured to the support structure as by means such as clamp elements 9 and 10, and bolts 11 and 12. Although not always necessary or essential, gasket seals may be inserted between the plate elements and the support structure to which applied.

The upper plate elements 13, while similar to the lower plate elements 8, are provided with peripheral edge portions 13a and 13b of which 55 the portions 13a are provided for juncture with

3

similar portions of adjoining elements. As shown, they are turned upwardly to form a vertical lip or rim adapted to be secured to that of the adjoining element as by means of bolts 14. The edge portions 13b, adjoining the vessel wall 5 are turned downwardly to engage the upper surface of the lower plate edge portions. Other and conventional means may be employed for assembling the tray structure contemplated.

Both upper and lower plate elements are provided with a plurality of generally tubular, vertical chimney elements 15 and 16 of substantially equal length opening through the respective plates 8 and 13, and terminating in jagged or serrated peripheral edge portions 15a and 16a. 15 The length of said chimney elements will determine the length of the edge portions 13b, which also will be substantially equal to that of the chimney elements.

In each plate member, the chimney elements are disposed in rows, and in uniformly spaced relation one to another in each row, and from row to row. In any two rows, four adjoining arrangement of each plate is therefore characterized as having a square pitch. Also in each plate element the chimney elements are spaced individually and from row to row so as to provide a substantially continuous, flat, intermediate plate surface between elements and surrounding each element.

In assembling the plates to form a tray member, a lower plate element is disposed with its chimney elements extended upwardly, and an upper plate element is disposed with its chimney elements extending downwardly, the chimney elements of each plate making contact with the plate surface intermediate the elements of the other plate. Also in assembling the plates in this fashion, provision is made such that from 40 plate to plate the rows of chimney elements are alternately disposed, and that the individual elements of one plate are in offset relation to those of an opposed plate. By this arrangement an overall pattern of chimney elements is provided in which any two elements of one plate with an adjoining element of an opposed plate will form the corners of a triangle. Such an arrangement is therefore characterized as having a triangular pitch.

In addition to the clamps and bolts provided for joining the lower plate elements to the support structure, and for uniting elements 13 one to another, means is provided for maintaining the assembled upper and lower plate members as a unitary tray structure. One such means is provided by cross-bar elements 17 spanning a chimney element opening in one plate and a hold down bolt 11a extended through the chimney and a bolt hold in an opposed plate. Also, as shown in Fig. 2, the means for securing the tray to annular support ring 4 may function in addition as a means for maintaining the assembly of plate elements. In this arrangement, the bolts 12 extend through both the upper and lower plates to engage the upper plate element against the lower element, and the ring 4 between the lower element and clamp member 10.

The lower tray assembly illustrated in Fig. 2 is also shown partially in plan view in Fig. 1. It is composed of a plurality of pre-formed sections individually assembled exteriorly of the tower, and installed and mounted in the tower to form a complete tray structure. As shown, each section is composed of two plate elements 18 and 23 75

respectively. These plate elements correspond in general to the elements 8 and 13 respectively of the upper tray in Fig. 2, being provided with similar chimney elements 25 and 26 which are formed and arranged in a pattern such as described with reference to the upper tray. In certain other respects the structure differs.

As illustrated, each upper and lower plate element is formed with rim portions 18a and 23a respectively, of which the peripheral edges are turned inwardly as shown. Each rim portion has an overall height equal to about one half that of a chimney element. The assembly as a sectional unit may be accomplished as by means of peripheral stud bolts 21 mounted on one plate element adjacent the rim portion thereof and adapted to extend through a corresponding bolt hole in the opposite element to receive a nut 21a. Preferably only the inner edges of the plate sections are joined in this manner, the outer edges, adjacent the tower wall, being secured by means of a combination bolt member 22 which extends through both upper and lower plate elements which are then held between nuts 22a and 22b. The bolt 22 is designed and located so as to receive a clamp member 20 and so as to permit engagement of the tower ring 4 between the clamp and the lower plate element 18. This same combination means may also be employed at the inner edges, if the support members are such as to permit employment of a clamp arrangement such as member 28; for example if the support members are I-beams. As shown, however, the several tray sections are secured to the support members as by means of bolt members 28 and associated clamps 29. In mounting the sections they are slightly spaced one from another and from the tower wall as required to allow for expansion. In addition to the peripheral bolting means, the plate members also may be secured to one another by elements 27 and bolts 27a identical or similar to the elements 11 and 11a shown in conjunction with the upper tray structure. In the lower tray assembly illustrated in Fig. 2, the juncture between the upper and lower plate elements is provided with a fluid-tight edge seal by means such as a metal gasket 30.

In Fig. 3, an alternate assembly and mounting arrangement is shown, in which the inner rim edge portions of adjoining plate members are joined by means of stud bolts 31 secured to the upper surface of the lower plate elements 18. The bolts 31 extend upwardly through corresponding bolt holes in the upper plate elements 23 so as to receive angle clamp members 32 held by means of nuts 31a. The angular clamp elements are disposed in opposed relation along adjoining section edges, and the upstanding legs 32a may be bolted together. Preferably, however, this form of clamping means is employed in conjunction with a vertical baffle and distributor element 33 secured by one edge portion to a support member and extended laterally of the vessel in perpendicular relation to the direction of flow across the assembled tray, as from a downcomer baffle 7 toward a weir 6.

The apparatus when assembled in the manner illustrated and described is operated in the conventional fashion. Liquid flows downwardly through the tower from plate to plate by way of the downcomers, with a head of liquid established on each plate by the height of weirs 6. Where used, the baffle elements 33 aid in establishing a more uniform minimum liquid level and also by suitable shaping they may aid in distribution of liquid flow over the plate surface. Vapors or

gases pass upwardly through the tower by way of the plate chimney openings.

When operation of the tower is initiated, liquid is introduced at an upper level in the tower at a rate substantially as required to flood the several trays in succession. At this stage the space between plate elements of the trays may fill with liquid and liquid may spill through the lower plate chimney elements. But upon initiating upward flow of gaseous materials through the tower, the liquid which may originally be trapped between the plate elements is forced out and upwardly into the layer of liquid flowing across the trays.

In any tower of the character contemplated and described, the liquid flowing across the trays is usually agitated violently by the gaseous materials passed through the trays. In a typical bubble cap tray, in which the gaseous material issues more or less laterally from notched bubble caps, the agitation effect may be such as to cause considerable spray and froth to be thrown upwardly toward the tray above, and consequently to cause entrainment whereby the liquid is carried upwardly through the plate next above with the gaseous materials, and resulting in undesired and uncontrolled liquid reflux or recycling. Such excessive agitation also tends to interfere with suitable liquid flow characteristics, increasing holdup time on the trays, and also resulting in surging and otherwise to interfere with uniform operation.

In a tray structure according to the present invention, initial agitation occurs well below the surface of the tray liquid, and in the substantially confined zone of the downwardly extended, upper plate chimney elements, and a considerable part of the gas velocity is dissipated before it reaches the tray liquid surface. Consequently, excessive agitation and liquid entrainment will be reduced, and liquid flow characteristics become more uniform.

It is contemplated that the plate elements may be made of comparatively light weight, thin gauge metals, and preferably not more than 10 gauge materials. The chimney elements as shown may be formed by die punching in deep drawing dies such that the punch will first draw and deform the metal and then rupture it to provide the jagged or serrated peripheral edge portions at the end of each chimney. Although the serrated edge thus formed may not be uniform, normal variations will not greatly affect the overall length of the chimney element nor its operating characteristics. If greater uniformity is required, the punch or mandrel element employed may be provided with a series of radially disposed ridges designed to induce rupture of the metal along predetermined lines. Alternatively the sheet may be scored before drawing and punching to obtain the same result. In a typical tray structure according to this invention, the chimney elements should have an overall height or length substantially equal to the diameter thereof at the serrated end. In one preferred form of the apparatus, these dimensions would be about one and one half inches, or two inches. The opposite end of the chimney element is preferably formed with a smoothly curved, expanded opening through the plate, of slightly greater diameter than the serrated end.

What is claimed is:

1. A fractionating tray structure comprising upper and lower plate members disposed in op-

posed parallel spaced relation one to another, a plurality of tubular chimney elements opening through each plate member, each leaving a peripherally serrated end edge portion, the chimney elements of one member being offset with relation to those of the other member and extending into surface contact with the opposite plate member, and means for joining said members rigidly one to another.

2. A tray structure according to claim 1 in which the chimney elements of each member are arranged in parallel rows and in a square pitch relationship, the rows of one member being intermediate the rows of the opposite member, and with the individual elements of one plate member in offset relation to those of the other member longitudinally of said rows, whereby said elements are disposed in a triangular pitch relationship from plate member to plate member.

3. A tray structure according to claim 1, in which said plate members comprise a plurality of sectional elements of which the elements of one member are individually secured to a supporting structure for said tray, and the elements of the other member are joined one to another and to said individually supported elements.

4. A tray structure according to claim 1, in which said upper and lower plate members comprise a plurality of sectional elements of which individual upper and lower elements are joined one to another in substantially fluid-tight relation to form a plurality of unitary tray sections, said sections being secured into supporting structure in edgewise relation to form said tray.

5. A tray structure according to claim 4, in which the supporting structure is provided with a parallel series of baffle plate elements extending upwardly therefrom between edge portions of adjoining tray sections carried thereon.

6. A tray structure according to claim 5, in which said tray sections are secured to said baffle elements along parallel adjoining section edge portions.

7. A tray structure for fractionation towers and the like, comprising a pair of individual plate members joined together as a unit in vertically spaced relation one to another, a plurality of tubular chimney elements of substantially equal length associated with each plate member joined at one end to a plate member surface and opening therethrough, the other end of each element terminating in a peripherally serrated, end edge portion, said elements disposed in peripherally spaced relation one to another over said plate members providing a substantially continuous, flat, intermediate plate surface portion between and surrounding each element, the chimney elements of one plate member being offset radially with respect to those of the other member in said pair, and means for rigidly uniting said plate members, the serrated edge portions of the chimney elements of at least one member in said pair engaging the intermediate surface portions of the other member and spacing said members from one another by substantially the length of said elements.

JAMES M. BALLENGER.
